(57) **CLAIM**

I claim the ornamental design for an protective cover for containing and reading a compact disc, as shown and described.

DESCRIPTION

FIG. 1 is a bottom and side perspective view of an protective cover for containing and reading a compact disc showing my new design;

FIG. 2 is a bottom plan view thereof;

FIG. 3 is a top plan view thereof;

FIG. 4 is a side elevational view thereof taken from the bottom of FIG. 2;

FIG. 5 is a side elevational view thereof taken from the top of FIG. 2; and,

FIG. 6 is a side elevational view thereof taken from the right side of FIG. 3, the side elevational view taken from the left side of FIG. 3 is a mirror image thereof.

1 Claim, 3 Drawing Sheets

FIG. 1.

FIG. 2.

FIG. 4.

FIG. 5

FIG. 3.

FIG. 6.
